United States Patent Office

Des. 187,935
Patented May 17, 1960

187,935

CLOCK

Mary M. Weitzel, Upland, Calif.

Application February 9, 1959, Serial No. 54,533

Term of patent 3½ years

(Cl. D42—7)

FIG. 1.

FIG. 2.

Figure 1 is a perspective view of a clock, showing my new design; and

Figure 2 is a side elevational view thereof.

I claim:

The ornamental design for a clock, as shown.

References Cited in the file of this patent

UNITED STATES PATENTS

D. 131,685 Goldberg ----- Mar. 24, 1942